UNITED STATES PATENT OFFICE.

JOHN O'BRIEN, OF STAYNER, ONTARIO, CANADA.

SCREEN.

1,286,888.

Specification of Letters Patent.

Patented Dec. 3, 1918.

Application filed March 26, 1918. Serial No. 224,711.

To all whom it may concern:

Be it known that I, JOHN O'BRIEN, a subject of the King of Great Britain, and resident of the town of Stayner, county of Simcoe, Province of Ontario, in the Dominion of Canada, have invented certain new and useful Improvements in Screens, of which the following is a specification.

The invention relates to improvements in screens as described in the present specification and illustrated in the accompanying drawings that form a part of the same.

The invention consists essentially of the novel construction and arrangement of parts whereby a screen is provided with openings adapted to permit the passage of insects in one direction only.

The objects of the invention are to provide a screen through which insects may pass outwardly and cannot return, to facilitate the proper ventilation of rooms and generally to provide a screen which will be inexpensive to manufacture, durable and efficient.

In the drawings Figure 1 is a view of the outer side of the screen showing the insect passages.

Fig. 2 shows a modified form of screen with means for adjusting the length of the same.

Fig. 3 is a cross sectional view through substantially the center of Fig. 2.

Fig. 4 is a cross sectional view through the screen shown in Fig. 1.

Like numerals of reference indicate corresponding parts in each figure.

Referring to the drawings, the frame in which the netting is supported is composed of vertical end members 1 preferably of a width to correspond to the thickness of the window or door which it replaces, a bottom member 2 connecting said end members and having upwardly turned flanges 3 and 4, and a top member 5 having its outer portion 6 turned downwardly a considerable distance and having its lower end bent to form jaws 7 to receive an end of the wire netting.

The wire netting 8 is securely fastened to the flange 4 of the bottom and to the end members 1 and extends upwardly to within a short distance of the top 5 and is then turned forwardly and downwardly at an acute angle and secured in the jaws 7.

The netting at the point of bending is

provided with a plurality of openings 9 through which the insects may pass outwardly but through which they cannot return owing to the acuteness of the angle at the point where said openings are located. 60

To provide a means of adjusting the length of the screen to properly fit the window or door an extension member 10 consisting of a box like frame having flanges 11 slidably arranged over the top and bottom 65 of the screen frame is provided, said frame having in the interior thereof tensioned springs 12 adapted to hold the device in close engagement with the sides of the window or door.

In Figs. 2 and 3 a modified form of adjustable screen is shown in which the frame is made in two sections 13 and 14, the section 13 being slidably arranged within the section 14. 70

Owing to the friction caused by continuous sliding of one frame within the other it is preferable to cover the net at the point of bending with metal strips 15 and 16 through which the openings 9 extend, the 80 strip 16 having its edge suitably bent to form a slot in which the strip 15 slides.

In the use of the invention the window is raised and the screen placed in the opening, the window being then drawn down to 85 closely engage the top thereof, and as the insects light on the inner side of the netting they will crawl upwardly thereon and pass out through the openings 9 through which they cannot return. 90

What I claim is:—

In a screen, a pair of frames telescopically arranged one within the other, a wire mesh section secured to each of said frames and adjacent to the tops of said frames being turned forwardly at an acute angle and secured to the front wall of the corresponding frame, metal guides secured to the front walls of said frames and extending over the bent portions of said wire mesh sections and being slidably arranged one within the other and insect openings through said guides and through said wire mesh sections at the points of bending. 95

Signed at the town of Stayner, Ont., this 105 21st day of August, 1917.

JOHN O'BRIEN.
